Primary Examiner — John R Yeh*(74) Attorney, Agent, or Firm* — Ellenoff Grossman & Schole LLP; James M. Smedley; Alex Korona(57) **CLAIM**

We claim the ornamental design for a long handle scraper, as shown and described.

DESCRIPTION

FIG. 1 is a top, right side perspective view of our new design for a long handle scraper;

FIG. 2 is a bottom, left side perspective view thereof;

FIG. 3 is a top view thereof;

FIG. 4 is a bottom view thereof;

FIG. 5 is front view thereof;

FIG. 6 is a rear side view thereof;

FIG. 7 is a right side view thereof; and,

FIG. 8 is a left side view thereof.

The shading lines shown in the drawings represent the approximate three-dimensional contour of the design, and are not intended to indicate surface decoration.

The broken line(s) in the drawings depict portions of the long handle scraper that form no part of the claimed design.
